ATTORNEY

UNITED STATES PATENT OFFICE.

LOUIS J. WESTNESS, OF MILWAUKEE, WISCONSIN.

WINDOW ATTACHMENT.

1,242,290.

specification of Letters Patent.

Patented Oct. 9, 1917.

Application filed July 22, 1916. Serial No. 110,622.

To all whom it may concern:

Be it known that I, LOUIS J. WESTNESS, a citizen of the United States, and resident of Milwaukee, in the county of Milwaukee and State of Wisconsin, have invented new and useful Improvements in Window Attachments, of which the following is a description; reference being had to the accompanying drawings, which are a part of this specification.

This invention has for its object to provide an attachment for windows which will enable their being swung from the casing to permit ready access thereto for cleaning.

Another object of the invention is to make such an attachment which will be strong and durable for the purpose and which may be readily placed in operative position and when removed will leave the window sash and its casing free from conspicuous permanent fastenings.

Another object of the invention is to provide such an attachment which may be inexpensive and which may be easily installed without material alteration of the wood-work.

With the above and other objects in view the invention consists in the window attachment as herein claimed and all equivalents.

Referring to the accompanying drawings, in which like characters of reference indicate the same parts in the different views,

Figure 1 is a sectional elevation of a window equipped with the window attachment of this invention and showing the lower sash pivotally mounted on the attachment and ready to be swung from the casing;

Fig. 2 is a sectional plan view thereof with the parts in the same position;

Fig. 3 is a similar sectional plan view showing the window sash swung out of the casing;

Fig. 4 is a detail view of the lower end of the hinge bar showing the clamping member in its open position;

Fig. 5 is a similar view with the clamping member in its closed or locked position; and

Fig. 6 is an edge view thereof in this position.

In these drawings 10 indicates a window casing provided with sash stops 11 and 12 forming guide grooves between them for the window sash 13 as usual. The sash stop 12 at suitable points has wood screws 14 fastened thereto with their heads slightly pro-

jecting so as to be adapted to receive key-hole slots 15 of a flat hinge bar 16 which is thus adapted to be secured in place against the sash stop. The keyhole slots 15 have 60 their smaller ends uppermost so that the weight of the hinge bar and the part supported by it tends to hold it securely in its engagement with the ends of the screws 14. To more effectively secure the hinge bar in 65 place, however, a camlocking member 17 consisting of a flat metal lever is pivotally mounted near the lower end of the hinge bar 16 and has a cam shaped notch 18 to engage the shank of one of the screws 14, 70 and the cam action of the notch is such that as the clamping member is swung from its open position shown in Fig. 4 to its closed position shown in Fig. 5 it bears upwardly on the shank of the screw, thus drawing the 75 hinge bar 16 downwardly into locking engagement with all of the screws 14 and bringing its rounded lower end 19 into bearing engagement with the sill of the window frame. The front edge of the clamping 80 member 17 is preferably bent out to form a projection 20 by means of which it may be readily swung.

Upstanding hook members 21 are secured to or formed with the hinge bar 16 at its 85 rear or outer edge and one of them forms a stop for engaging a shoulder 22 on the clamping member 17 for limiting the outward movement of said clamping member as shown in Fig. 4.

One side stile of the window sash 13 has pivot eyes thereon formed by cotter pins 23 passing therethrough and the loops or eyes of these cotter pins are elongated and adapted to fit upon the upstanding points of the 95 hook members 21, the latter being enlarged and flattened to form heads which are free to pass through the elongated eyes of the cotter pins when the sash is in place in the window frame as shown in Fig. 2, but which 100 prevent the removal of the cotter pins therefrom when the sash is swung outwardly as shown in Fig. 3.

With the window attachment of this invention the window sash may be readily 105 swung inwardly into the room for cleaning, it being only necessary to attach the hinge bar by placing it on the projecting ends of screws 14 and then swinging the clamping member 17 to its clamping position. This 110 draws the hinge bar downwardly into firm engagement with the screws 14 so as to be

held by the heads thereof and also moves it into bearing engagement with the window sill. The sash which has been previously raised slightly is then lowered to pass the 5 elongated loops of the cotter pins 23 over the heads of the hooks 21. While the weight of the sash is thus supported by the hinge bar 16 the sash may be swung out of the casing and into the room where it is convenient for cleaning, the opposite sash stop 12 being removed for this purpose. While the sash is thus swung on the pivot hooks 21 of the hinge bar it is incapable of being lifted off of the hooks because of the flat 15 heads of the hooks lying across the elongated slots of the pivot eyes, as shown in Fig. 3. When the window has been cleaned it is quickly restored by swinging it back into the frame and replacing the far sash stop 20 12 and then raising the sash off the pivot hooks 21. By swinging the clamping member 17 upwardly the upper surface of its cam notch bears on the shank of the screw 14 to lift the hinge bar and thus bring all 25 of the keyhole openings 15 into position to readily pass over the heads of the screws 14. The hinge bar is quickly and easily placed in operative position and removed therefrom, while the swinging of the window sash thereon may also be accomplished with ease and without loss of time, so that 30 the use of the present invention will permit of the cleaning of the windows from within the room with a saving of time and without the danger incident to the ordinary method. The wood screws 14 and the pivot eyes 23 are the only parts remaining in place after the hinge bar has been removed so that the equipment is inconspicuous and 35 does not mar the appearance of the window. It is inexpensive and does not require material alteration for its installation, and still is strong and durable in use and highly efficient for the purpose intended.

40

45 While the metal strip has been shown and described as removably secured to the casing or the sash stop forming a part there-

of, it is obvious that it may be removably attached to the window sash and have its hook members positioned to engage eye 50 members on the casing. Such reversal of position of parts is intended to be included in the claimed invention.

What I claim as new and desire to secure by Letters Patent is:

55 1. In combination with a window, an attachment thereto, comprising a metal strip having slotted openings, headed projections on the side of the window casing adapted to fit in said openings to removably secure the strip in place, a clamping lever fulcrumed on the metal strip and having cams for moving the metal strip from a position in which the headed projections lie within the larger portions of the openings to a position in 60 which they lie within the slotted portions of the openings and for moving it back again, hooks projecting from the metal strip, and eye members projecting from the window sash and adapted to engage the hooks 70 and form the hinge connection for the window sash.

2. In combination with a window, an attachment therefor comprising a metal strip having openings, headed projections on the 75 side of the window casing adapted to fit in said openings to removably secure the strip in place, a clamping lever fulcrumed on the metal strip and having a cam notch engaging one of the headed projections for moving the metal strip into engagement with the window sill when the metal strip is secured in place, hooks projecting from the metal strip, and eye members projecting from the window sash and adapted to engage the hooks and form the hinge connection for the window sash.

In testimony whereof, I affix my signature, in presence of two witnesses.

LOUIS J. WESTNESS.
